CLAIM

The ornamental design for a stylus pen, as shown and described.

DESCRIPTION

FIG. 1 is a front, right and bottom perspective view of a first embodiment of a stylus pen, showing my new design; FIG. 2 is a rear, left and top perspective view thereof; FIG. 3 is a front view thereof; FIG. 4 is a rear view thereof; FIG. 5 is a left side view thereof; FIG. 6 is a right side view thereof; FIG. 7 is an enlarged top plan view thereof; and FIG. 8 is an enlarged bottom plan view thereof; and, FIG. 9 is an enlarged view of portion of FIG. 1 thereof. The broken line showing of the stylus pen is for the purpose of illustrating article and forms no part of the claimed design.
